UNITED STATES PATENT OFFICE

LEWIS A. JAMES, OF FREDONIA, KANSAS

WASHING MACHINE

Application filed February 7, 1929. Serial No. 338,204.

This invention relates to a washing machine and has for its prime object to provide a mechanism for washing clothes which utilizes a receptacle with water therein and an agitator mounted in the receptacle for oscillatory movement and having means for submerging a quantity of air in the water and allowing this air to be fixed in the water among the clothes therein.

10 Another very important object of the invention resides in the provision of a mechanism of this nature wherein the agitator operates to turn the clothes over.

A still further very important object of the invention resides in the provision of a washing machine of this nature which is simple in construction, inexpensive to manufacture, strong and durable, thoroughly efficient and reliable in use and operation, not 20 likely to easily become out of order, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

30 Figure 1 is an end elevation of the washing machine embodying the features of my invention,

Figure 2 is a vertical longitudinal section therethrough taken substantially on the line 35 2—2 of Figure 1,

Figure 3 is a transverse vertical section taken substantially on the line 3—3 of Figure 2,

Figure 4 is a perspective view of the oscillator.

Referring to the drawing in detail, it will be seen that the numeral 5 denotes a receptacle which includes a semi-cylindrical bottom 6 and is closed at its top by a removable

45 lid 7. A bearing 8 is mounted in one side of the receptacle and a bearing 9 is mounted in the other side thereof, these bearings being concentrically disposed in respect to the bottom 6. An agitator is denoted generally by 50 the letter A and includes a hollow body por-

tion formed by walls 10 joined together at longitudinal edges, said juncture being provided with apertures 11 and diverging away from each other from said joined edges and a curved wall 12 which is provided near its 55 side edges with series of apertures 14.

Thus this body is substantially triangular in cross section and has openings adjacent or directly at the corners thereof. The walls 10 of the body are provided at their ends with right angularly extending flanges or ears 15 which are riveted or otherwise secured as at 16 to spaced parallel coextensive arms 17 on the extremities of which are laterally and outwardly projecting pintles 18 and 19.

The pintle 18 is journaled in the bearing 8 while the pintle 19 is journaled in the bearing 9 and extends therethrough terminating outwardly of the casing in order that a hand crank 20 may be secured thereto.

70 A stuffing box 21 is engaged with the bearing 9 about the pintle 19.

When the body of the agitator is in the position shown in Figure 3 it will be seen that water in the body will drain out of the 75 bottom series of openings 14 and air be drawn into the top series of openings 14 and also through openings 11.

As the crank is oscillated and the body of the agitator submerged it will be seen that 80 the air trapped in the body will escape upwardly through openings 11 through the water among the clothes therein and any clothes immediately under the body will be taken down in the water with the body and as the body reaches the other end of its oscillation, said clothes will have been turned over completely.

The body of the agitator in no way functions as a beater but rather serves to throw 90 the clothes from one side to the other and completely turn them over and the air comes in from the body when submerged to mix with the clothes.

On one side of the receptacle there is provided a block 25 adjacent the top of the receptacle and functions as a stop that is limits the upward movement of the agitator as is apparent from an inspection of Figures 2 and 3.

The receptacle may be mounted on any suitable support 26. The oscillation of the agitator may be occasioned either by hand power as indicated in the present embodiment or by any suitable motor power if so desired. In fact the present embodiment of the invention has been disclosed in considerable detail merely for the purposes of exemplification since in actual practice its attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

- 20 1. In a washing machine of the class described, a receptacle formed with a semi-cylindrical bottom, bearings in the sides of the receptacle concentric in respect to the bottom, arms having pintles journaled in the bearings, a cross member between the arms of hollow construction and provided with openings, said member being triangular in cross section and said openings being disposed at the corners thereof.
- 25 2. An agitator for a washing machine comprising a body formed of a pair of elongated diverging walls having longitudinal edges joined together and provided with a series of apertures through the joint thereof, and a plate mounted between the free longitudinal marginal portions of the walls having its opposite side edges secured thereto and having apertures adjacent said side edges, and means for movably supporting the body.
- 30 3. An agitator for a washing machine comprising a pair of elongated diverging walls having longitudinal edges joined together and provided with a series of apertures at the joint thereof for the passage of air, a plate mounted between the free marginal portions of the walls and secured thereto along its longitudinal edges, said plate having apertures adjacent said longitudinal edges for the passage of water, said plate being transversely curved, integral ears formed on the opposite ends of the walls and supporting arms rigidly secured to the ears.
- 35 4. In testimony whereof I affix my signature.
LEWIS A. JAMES.
